UNITED STATES PATENT OFFICE.

ALEXANDER N. SCHANSCHIEFF, OF VALLEY STREAM, NEW YORK, ASSIGNOR TO
FERDINAND STRAUSS, INC., OF NEW YORK, N. Y., A CORPORATION OF NEW YORK.

DESIGN FOR A CHILD'S TOY.

52,291.

Specification for Design.

Patented Aug. 20, 1918.

Application filed November 14, 1917. Serial No. 202,063. Term of patent 3½ years.

To all whom it may concern:

Be it known that I, ALEXANDER N. SCHANSCHIEFF, a citizen of the United States of America, residing at Valley Stream, Nassau county, and State of New York, have invented a new, original, and ornamental Design for a Child's Toy, of which the following is a specification, reference being had to the accompanying drawing, forming part hereof, which represents a perspective view of a toy embodying my new design.

I claim:

A design for a child's toy simulating a wagon of novel form substantially as shown.

Signed at New York city, New York, this 3rd day of November, nineteen hundred and seventeen.

ALEXANDER N. SCHANSCHIEFF.

Witnesses:

EDWARD A. JARVIS,
MAURICE BLOCK.
